[57] ABSTRACT

The base comprises a base plate having a plurality of slots formed therein, for receiving mounting bolts for machinery frames for mounting the machinery to the base plate, in which some of the slots have a greater width than the diameters of the shanks of the bolts used therewith. Accordingly, the wider slots restrain the bolts at only one side thereof against lateral movement. In addition, a strap coupled to an adjustment bolt is disposed below the slots being used, so that the machinery mounted thereabove can be displaced lengthwise along the base plate. The strap has threaded holes for engaging the machinery mounting bolts.

FIG. I

FIG. 2

MACHINERY MOUNTING BASE

This invention pertains to bases for mounting machinery, and in particular to base plates which accommodate differently-dimensioned machinery in which the mounting frames or feet, and the fasteners used therewith, are differently spaced-apart.

Base plates in the prior art are already known to have a plurality of slots so that differently-dimensioned machinery, having differently patterned mounting feet and variously-spaced fastening hardware can be used alternately on the same base plate. In this prior art it is arranged that these slots are formed in parallel, so that wider machinery frames can be fastened onto the same base plate which will also accommodate narrower machinery frames. The difficulty with this prior art arrangement arises from the fact that, in many circumstances, it is impossible to provision a sufficient number of parallel slots to accommodate many differently-dimensioned and similarly dimensioned machinery frames. That is, many machinery frames have mounting area dimensions with such small gradations therebetween, one from another, that there is not sufficient spacing to provide metal between what would otherwise be adjacent, frame-accommodating slots.

To overcome this difficulty in the prior art, it has been the practice to affix separate fastening slide rails between the machinery and the base plate. So also, obviously, it is a common practice to provide a separate base plate for each, differently-dimensioned item of machinery. Patently, these prior practices are expensive.

It is an object of this invention to set forth an improved base plate which avoids the prior art difficulties.

It is an object of this invention in particular to provide base means for fastener-mounting of machinery thereto, comprising a base plate; said base plate having means for receiving machinery-mounting fasteners, and wherein said fastener-receiving means includes at least a first plurality of means for restraining only one side of the machinery-mounting fasteners against lateral movement.

A feature of this invention comprises the provisioning of a base plate having a plurality of slots formed therein for receiving mounting bolts for machinery frames for mounting the machinery to the base plate, in which some of the slots have a greater width than the diameters of the shanks of the bolts used therewith. Accordingly, the wider slots restrain the bolts at only one side thereof against lateral movement. In addition, a strap coupled to an adjustment bolt is disposed below the slots being used, so that the machinery mounted thereabove can be displaced lengthwise along the base plate. The strap has threaded holes for engaging the machinery mounting bolts.

Further objects and features of this invention will become more apparent by reference to the following description taken in conjunction with the accompanying figures in which:

FIG. 1 is a plan view of the inventive base means, according to the invention; and

FIG. 2 is a side elevational view, partially in cross-section, of the base means of FIG. 1.

As shown in FIGS. 1 and 2, the base means 10 comprises a base plate 12 having pluralities of slots 14 and 16 which lie parallel with the plate longitudinal axis.

Slots 14 have a width which is complementary to the diameter of the shanks of fasteners normally to be used for the mounting of machinery. Slots 16, on the contrary, are wider, having a width in excess of that required for the diameter of the shank of fasteners used to mount machinery to the base plate. Such fasteners, as bolts 18 in penetration of a machine mounting frame (only a portion being shown), in FIG. 2, are received in a pair of slots 16.

10 In FIG. 1 are set out several patterns of bolt shank diameters. For instance, there are shown four shank diameter representations 22, illustrative of one pattern. Two of these diameters 22 are shown disposed against the outer side of slots 16 on one side of the base plate 12, and the two other bore diameters 22 are shown disposed against the outer side of the other slots 16. Accordingly, machinery mounted to the base plate 12, with the bores in penetration of the slots 16 is restrained against lateral movement, even though the slots are excessively wide.

15 The shank diameter representations 24 through 28 illustrate the use of other patterns for mounting other machinery to the same base plate using the slots provided. In some of these, specifically diameters 26, it can be seen that the narrower slots 14 can be used in conjunction with the wider slots 16 for mounting machinery having a mounting frame dimension and bolt centers distances which warrant fasteners set out in such a particular pattern.

20 30 The patterns represented by shank diameters 22 through 28 warrant the use of 4 slots, two toward one end of the base plate 12, and two "inboard" thereof, because of the "reach" of mounting fasteners for certain types of machinery anticipated for mounting to plate 12. However, if other machinery is to be mounted, and the hold-down bolt centers distance does not require the use of four slots, a pair of juxtaposed slots works equally well, as illustrated by the patterns set out for shank diameters 30 and 32.

35 40 The base plate 12 comprises a pair of side walls 34 which support a deck 36. Beneath the deck 36 is a strap 38 which has a plurality of spaced-apart threaded holes 40 formed therein for receiving threaded shank portions of bolts 18. Strap 38 has a perpendicularly extending tab 42 which also has a threaded bore 44 for threadedly receiving an adjustment bolt 46. Bolt 46 has a drive head 48 which is restrained by a clip 50 supported on one end of the deck 36.

45 50 It is proposed that a pair of straps 38 and the associated bolt 46 and clip 50 can be used underneath the base plate 12 for two purposes: for one, the straps 38 receive and secure the mounting bolts, and serve the purpose of locking nuts. Additionally, if the machine mounted to the base plate 12 comprises a motor, or the like, having a pulley, or whatever, for receiving a drive belt (for driving or receiving drive from, associated machinery), bolt 46 and strap 38 provide means for adjusting the position of the machinery in order that the drive belt might be tensioned and slackened as warranted.

55 60 While I have described my invention in connection with a specific embodiment thereof, it is to be clearly understood that this is done only by way of example and not as a limitation to the scope of my invention as set forth in the objects thereof and in the appended claims.

65 I claim:

1. Base means, for fastener-mounting of machinery thereto, comprising:
 a base plate, having an axis;
 said base plate having means for receiving machinery-mounting fasteners; and wherein
 said fastener-receiving means includes first and second means for restraining sides of machinery-mounting fasteners against lateral movement relative to said axis;
 both said first and second means comprise surfaces of common axial length, and parallel fully throughout said length, formed in said base plate for contacting said sides of machinery-mounting fasteners; 10
 said surfaces of said first means being spaced apart a prescribed distance to effect a common contacting engagement with opposite sides of given fasteners; and
 said surfaces of said second means being spaced apart more than said prescribed distance to effect 20 a contacting engagement only with either one of opposite sides of such given fasteners.
2. Base means, according to claim 1, wherein:
 said base plate has a plurality of walled slots formed therein; and
 said walls define said surfaces. 25
3. Base means, according to claim 1, wherein:
 said base plate has a longitudinal axis; and
 said slots are linearly disposed parallel with said axis. 30
4. Base means, according to claim 3, further including:
 means for moving machinery-mounting fasteners, while the latter are in contact with said surfaces, axially along said slots. 35
5. Base means, according to claim 4, wherein:
 said moving means comprises means for engaging said fasteners and selectively and adjustably displacing the latter along said slots.
6. Base means, according to claim 5, wherein:
 said engaging and displacing means comprises a strap; 40
 said strap having a plurality of means for enveloping a portion of said fasteners; and further comprising

45

50

55

60

65

- adjustment means for selectively and adjustable displacing said strap axially relative to said slots.
7. Base means, according to claim 6, wherein:
 said plurality of enveloping means comprises spaced-apart holes formed in said strap for receiving said portions of said fasteners therein.
8. Base means, according to claim 7, wherein:
 said holes are threaded for receiving threaded portions of threaded machinery-mounting fasteners.
9. Base means, according to claim 6, wherein:
 said strap has a tab extending perpendicularly therefrom, said tab having a threaded hole formed therein; and
 said adjustment means comprises an adjustment screw rotatably secured at one end thereof to one end of said base plate, and having the other end thereof threadedly engaged with said hole in said tab.
10. Base means, according to claim 1, wherein:
 said fastener-engaging means further includes a second plurality of means for restraining only one side of the machinery-mounting fasteners against lateral movement.
11. Base means, according to claim 10, wherein:
 said first and second pluralities of restraining means are disposed in parallel.
12. Base means, according to claim 1, wherein:
 said fastener-engaging means further includes a second plurality of means for restraining opposite sides of machinery-mounting fasteners against lateral movement.
13. Base means, according to claim 12, wherein:
 said first and second pluralities of restraining means are disposed in parallel.
14. Base means, according to claim 12, wherein:
 said fasteners-engaging means further includes a third plurality of means for restraining opposite sides of the machinery-mounting fasteners against lateral movement.
15. Base means, according to claim 14, wherein:
 said first, second and third pluralities of restraining means are disposed in parallel.
